Lloyd H. Lipps,
by
John Stewart,
ATTORNEY.

UNITED STATES PATENT OFFICE.

LLOYD H. LIPPS, OF BETHLEHEM, PENNSYLVANIA.

APPARATUS FOR SPINNING.

Application filed February 2, 1923. Serial No. 616,572.

To all whom it may concern:

Be it known that I, LLOYD H. LIPPS, a citizen of the United States, residing at Bethlehem, in the county of Lehigh and State of Pennsylvania, have invented certain new and useful Improvements in Apparatus for Spinning, of which the following is a specification.

In spinning certain yarns, and especially silk or other fine yarns, it is found that on account of the twist working downward to the windings on the delivery package fibres projecting from these windings tend to become caught in the twist, and when they become so caught breakage of the yarn is a very likely consequence. This makes it impossible to put a high twist in the yarn without the process being made to proceed very slowly—so slowly that in fact there will be greater production if the spinning is performed in two operations (which is now the accepted and usual practice), the first so that the yarn gets a low twist, i. e., sufficient to bind the threads together and close or lay the fibres on them, and the second to put in the high twist. The object of this invention is to put in the yarn a high twist in a single high-speed operation, thus to considerably increase production. This I have found is possible by using the means hereinafter set forth and finally embodied in the appended claims.

In the accompanying drawing,

Fig. 1 is a front elevation of the delivery package, with its supporting and rotating means, the receiving spool and its supporting and rotating means, the thread traversing means and a flier embodying the invention;

Fig. 2 is a front elevation of the flier on a larger scale; and

Fig. 3 is a plan of the flier.

a designates the delivery windings of yarn on a spool *b* which is carried and rotated in the usual manner by a vertical spindle *c* suitably driven at the requisite speed. *d* is the receiving spool having its axis horizontal and its trunnions *e* or equivalent guided in the brackets *f*, *g* being a driving wheel on which the spool rests and by which it is driven. *h* is a traverse rail reciprocating horizontally and having a guide *h'* for the yarn, and *i* is a fixed yarn guide substantially in vertical alinement with the spindle. All these parts are well known and in common use.

In the following description of the improved flier it will be understood that all the details specified are not indispensable: The body *j* of the flier includes, in the illustrated example, a cylindrical metal shell *j'* and a core *j''* of wood or other lighter material, the object of this construction being to provide a hard peripheral surface on the body without unduly increasing its weight. The body has an axial hole *k* whereby it may be slipped over the spindle *c*. There are two light somewhat elastic wire arms *l* and *m*, respectively bent to form eyelets *l'* and *m'*. Arm *l* extends horizontally from the top of the body *j* and arm *m* extends first straight from the bottom of body *a* and then is bent downward at right angles. They are secured to the body both in the same way, to wit, as by grooving the end (upper or lower face of the body as the case may be) inward from its periphery, providing a hole in the body at the inner end of the groove, and then having bent down the inner end of the arm fitting the arm to this groove and hole, as shown in Figs. 2 and 3. Arm *l* is shorter and represents less mass than arm *m* and so to counterbalance the latter a weight *n* may be embedded in the body *c*. The eyelet *l'* stands in a horizontal plane, and eyelet *m'* in a vertical plane. The extent of the downwardly bent free end of arm *m* is such that when in rotation the flier rises (in a manner usual with fliers that are free on the spindle, as in the present case) as an incident of the draft of the yarn thereon there will be clearance between the latter and the upper flange of the spool *b* even when the uppermost windings *a* are delivering. The arm *l* projects but a short distance from body *j*, i. e., only sufficiently far so that there will be set up no appreciable ballooning of the yarn between *l'* and *i* as an incident of the rotation of the flier.

Arms *l* and *m* are so related to each other and to the body *j* that the latter stands between eyelets *l'* and *m'*, wherefore the stretch *A'* of yarn between the eyelets or guides *l'* and *m'* is maintained in a bend as shown in Fig. 3, or otherwise stated, has contact with the body *j*. This contact in the present example is at the periphery of the body. This is not indispensable, but it is probably the best way to provide the contact because it will continue effective and also result in an equitable amount of friction

being produced whatever angularity the stretch A' of yarn assumes with reference to the stretch A'' between l' and i on account of the arm in practice springing outward or tending to straighten as shown in dotted lines in Fig. 2 due to the action of centrifugal force.

In short, my invention contemplates providing a surface for contact of the yarn therewith so that by such contact and at the point thereof the twist put in the yarn will be checked in working downward from the take-up means (d) toward the delivery package (a) before it approximates and would thus catch the fibres of the windings of the package. Each guide of an ordinary flier at present tends to, though it does not actually, accomplish this purpose since the extent of contact is neither sufficient (and cannot be made so without unduly weighting the guide) nor is it steady enough. Wherefore my invention further contemplates affording this contact by means against which the yarn is held stretched between the two guides, and when this last condition exists it will be found that the spinning of yarn with a high twist can be performed in a single operation and with very materially increased production over known methods.

It is preferred that the guides maintain the stretched part A of the yarn at an angle acute to the plane in which each guide rotates, rather than at an angle acute to the axis of rotation, whereby wiping of the yarn on the said contact means occurs rather lengthwise than transversely of the yarn.

It will be understood that while the spool d is rotated from the wheel g to take up the spun yarn the spool a is by spindle c rotated clockwise as viewed in plan to put in the twist and that the flier is rotated in the same direction as the spool a, all as usual. When the normal speed is reached the flier will have risen under the draft of the yarn to about the dotted line position indicated in Fig. 1.

Having thus fully described my invention, what I claim as new and desire to secure by Letters Patent is:—

1. A yarn spinning organism including, with means to take up the spun yarn and means coactive therewith to spin the yarn

including a wound package and means to rotate the same around the axis of its windings, a pair of spaced guides freely rotative as a unit on said axis and through which the yarn successively extends from the package to the take-up means, and means, in contact with which the yarn is held stretched between said guides, to form a bend in the stretched part of the yarn and maintain said bend during any augmentation of the spinning speed.

2. A yarn spinning organism including, with means to take up the spun yarn and means coactive therewith to spin the yarn including a wound package and means to rotate the same around the axis of its windings, a flier freely rotative on said axis and including a pair of spaced guides through which the yarn successively extends from the package to the take-up means and means in contact with which the yarn is held stretched between said guides.

3. A yarn spinning organism including, with means to take up the spun yarn and means coactive therewith to spin the yarn including a wound package and means to rotate the same around the axis of its windings, a flier freely rotative on said axis and including a pair of arms having spaced guides through which the yarn successively extends from the package to the take-up means and a flier body from which said arms project and in contact with which the yarn is held stretched between said guides.

4. A yarn spinning organism including, with means to take up the spun yarn and means coactive therewith to spin the yarn including a wound package and means to rotate the same around the axis of its windings, a pair of spaced guides freely rotative as a unit on said axis and through which the yarn successively extends from the package to the take-up means, and means in contact with which the yarn is held stretched between said guides and with reference to which they rotate, said guides maintaining the stretched part of the yarn at an angle acute with respect to the plane in which each guide rotates.

In testimony whereof I affix my signature.

LLOYD H. LIPPS.
